UNITED STATES PATENT OFFICE

114,610

DESIGN FOR A DRESS

Robert Caine, New York, N. Y.

Application April 11, 1939, Serial No. 84,204

Term of patent 3½ years

To all whom it may concern:

Be it known that I, Robert Caine, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific flower and button appliques around the neck and sleeves as shown.

I claim:

The ornamental design for a dress, substantially as shown and described.

ROBERT CAINE.
